INVENTOR:

ADAM LICHT,

BY
FRED. FRAENZEL,
ATTORNEY

UNITED STATES PATENT OFFICE.

ADAM LICHT, OF NEWARK, NEW JERSEY.

EYEGLASSES.

SPECIFICATION forming part of Letters Patent No. 659,404, dated October 9, 1900.

Application filed October 20, 1899. Serial No. 734,157. (No model.)

To all whom it may concern:

Be it known that I, ADAM LICHT, a citizen of the United States, residing at Newark, in the county of Essex and State of New Jersey, 5 have invented certain new and useful Improvements in Eyeglasses; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention relates to improvements in 15 mountings for eyeglasses or spectacles, and more especially to a novel construction of strap or jaw and post to be used in connection with the spring and nose-guard of the glasses.

The invention has for its principal object 20 to provide a mounting for eyeglasses or spectacles which can readily be secured in position to the lenses or glasses without the danger of breaking or cracking the same by the pressure of the parts of the strap against the 25 faces of the lens while being secured in position.

A further object of this invention is to provide a novel means of securing the ends of the strap to the lens in such a manner as to remove 30 all strain from the lens and prevent cracking or breaking of the same.

A further object of the invention is to provide a pivotally-attached strap and a separate post having supports or legs made of spring 35 metal to produce greater resiliency of the parts and to provide a guard which when in position on the nose will result in greater comfort and ease to the wearer.

The invention therefore consists in the general construction of a mounting for eyeglasses or spectacles hereinafter set forth, as well as in the novel arrangements and details of the construction thereof, all of which will be more fully described in the accompanying specification, 45 and finally embodied in the clauses of the claim.

The invention is clearly illustrated in the accompanying drawings, in which—

Figure 1 is a perspective view of a pair of eyeglasses and a mounting therefor embodying the principles of my present invention. Fig. 2 represents a face view, on an enlarged

scale, of a portion of one of the eyeglass-lenses and a portion of the mounting connected therewith; and Fig. 3 is a horizontal section taken on line x in said Fig. 2. Fig. 4 is a perspective view of the strap, and Fig. 5 is a similar view of the form of post employed in connection with my invention. Figs. 6 and 7 are perspective views of modified forms of posts, 60 but which are all made according to the principles of this invention.

Similar letters of reference are employed in all of the said above-described views to indicate corresponding parts.

In the said drawings, A indicates the complete mounting, which comprises the usual form of spring b , connected at its free ends with the posts c and straps d to the glasses or lenses a . As will be seen from an inspection of Figs. 1, 2, and 3, each lens a is provided with a perforation a' , in which is preferably arranged a piece of flexible tubing a^2 , of rubber or other suitable material, and a^3 represents an ordinary pin or screw in said tubing for securing the strap d in position. 75 Each strap d comprises a box portion d' , in which there is a screw-threaded hole d^2 , and has a pair of arms d^3 , which are to be arranged on the opposite faces of the lens, and have perforations or holes d^4 to be placed directly over the perforations a' in the lens a , whereby the strap can be pivotally secured to the lens by means of the pin or screw a^3 , above mentioned, which is passed through said holes d^4 in the strap d and through the tube a^2 and secured in place, substantially as illustrated in Fig. 3. As shown in said figure, the tube a^2 is slightly longer than the thickness of the glass or lens a , whereby when the screw a^3 90 is screwed up tight in the holes of the arms d^3 of the straps d the ends a^4 of said tubing a^2 will be compressed between the surfaces of the lens and the inner surfaces of the said arms d^3 , thereby removing all undue pressure 95 and strain from the glass to prevent cracking or breaking of the same, but still permit the strap d to be operatively and pivotally secured to the lens. The strap d also has its box portion d' provided with oppositely-arranged and outwardly-extending lugs or projections d^5 .

One form of post c , such as I prefer to employ, is illustrated more particularly in Figs.

1, 2, 3, and 5, and it consists, essentially, of a cap or plate c' , which is provided with a hole or perforation c^2 , and has an arrangement of longitudinally-disposed shoulders or 5 projections c^3 , which with the said cap or plate c' will form a box-like portion of the post c . These shoulders or projections c^3 are made parallel, or approximately so, and near their junctions with the said cap or plate c' 10 the latter is curved to form a pair of grooves or channels c^4 and c^5 in the upper surface of the cap or plate and with a longitudinally-disposed groove or channel c^6 in the lower surface of the plate, as clearly illustrated in 15 said Fig. 5. Into the channels or grooves c^4 and c^5 are placed the end portions e' of yielding strap-pieces e , preferably made of spring-wire, said pieces being bent to form the 20 downwardly-projecting parts e^2 and the outwardly-extending parts e^3 , the latter being connected, as at e^4 , and the complete pieces e forming suitably-bent supports of the post c at opposite ends of the cap or plate c' of said post. 25 In the construction illustrated in Fig. 5 of the drawings the ends e' of the yielding strap-pieces e are simply laid in the grooves or channels c^4 and c^5 , and by means of pressure and without the use of solder these various parts are closed down tight and the 30 parts thereby securely fastened together to form a complete post; but it will be understood that the ends e' of the strap-pieces e may be secured to said plate or cap c' by means of solder. If desired, the ends e' of the 35 strap-pieces e may be secured directly to the edges c^7 of the cap or plate c by means of solder or in any other usual manner, as indicated in Fig. 6, or I may make the plate or 40 cap c and the supports in one integral piece, as indicated in Fig. 7, by providing the cap or plate c at its ends with the sheet-metal portions c^8 , which are bent downwardly, as at c^9 , and then outwardly, as at c^{10} , to form 45 suitable supports, as clearly illustrated in said Fig. 7. To secure the ends b' of the spring b and the posts d and straps together to provide the complete mounting A, the straps d are pivotally attached in position, 50 one to each lens or glass a , in the manner above set forth and as represented in the several figures of the drawings. I next place the cap or plate c' of one of the posts c against the box portion d' of the strap d , so that it 55 will extend partly into the central groove or recess c^6 in the under surface of the cap or plate c , with the curved lugs or projections d^5 of the box portion d' also extending into said groove or recess c^6 and the extreme free 60 end portions of said lugs or projections hugging the edges of the said cap or plate c , as indicated in dotted outline in Fig. 2 of the drawings. The perforated end b' of the spring b is then placed upon the outer surface of the 65 cap or plate c' , between the longitudinal shoulders or projections c^3 . Upon the end of the spring b and also between said shoulders

or projections c^3 is placed the perforated end f' of a nose-guard f , all of said parts being securely connected with the box portion d' 70 of the strap d and with the ends of the supports e resting against the edges of the glass or lens a , as illustrated, by the use of a screw or pin f^2 in the manner shown and as will be fully understood from an inspection of 75 Figs. 1, 2, and 3.

Of course it will be understood that the posts and straps at each end of the spring b for securing both lenses or glasses a to the mounting A are alike. 80

By my novel construction and arrangement of the parts as hereinabove described I have found that when the assembled parts have been securely connected by the screw f^2 the parts e^2 and e^3 of the yielding strap e will move in an outward direction, firmly gripping the edge of the lens. In this manner these parts substantially prevent pivotal movement of the spring. By the arrangement of the lugs d^5 , connected with the strap d , a cushion is provided to permit the screw f^2 to be fully screwed up and the several parts to be tightly drawn together without the least danger of cracking or breaking the lens. At the same time all undue strain is 95 removed from the lens at its point of connection with the pin a^3 , thereby allowing for proper expansion and contraction of the lenses.

The many advantages derived from my 100 present construction of mounting for eyeglasses or spectacles will be evident from the above description; but the principal features of my invention are the adaptability of readily and easily attaching the straps to the lens 105 without the least danger of cracking or breaking the glass by the strain due to great pressure between the various parts as heretofore made, and, furthermore, to loosely connect the arms of the strap with the lens at its point of 110 pivotal connection, thereby permitting the strap-pieces connected with the post during the assembling of the various parts to yield and readily adapt themselves to the curved edge of the lens or glass and to provide an 115 eyeglass-mounting which has a greater resiliency due to this arrangement of these yielding strap-pieces between the mounting and the lenses or glass at their points of attachment. Furthermore, by the arrangement of the longitudinally-arranged groove or channel c^6 in the under surface of the cap or plate c' of the post c any lateral movement between the said plate or cap and the box portion d' of the strap d is successfully overcome and a 125 better and more positive fastening has been produced. 120

I am aware that several changes may be made in the various arrangements and combinations of the parts comprising my novel 130 form of guard-mounting, as well as in the details of the construction thereof, without departing from the scope of my present invention. Hence I do not limit my invention to

the exact arrangements and combinations of the parts as herein described and illustrated in the accompanying drawings, nor do I confine myself to the exact details of the construction of such parts.

Having thus described my invention, what I claim is—

1. In a mounting for eyeglasses or spectacles, the combination, with a lens, the spring, and post, of a strap loosely and pivotally connected with the lens, a yielding strap device connected with said post having a pair of downwardly-projecting parts extending from the main portion of said device which is connected with the post, on opposite sides toward the edge of the lens, an outwardly-extending part connected with each downwardly-projecting part, extending in opposite directions and lying in holding engagement with the edge of the lens to substantially prevent the pivotal movement of the lens when the parts are secured together, a cushioning means connected with the said strap to permit of a movement of said strap in a direction toward the post, and means for positively connecting said spring, post and strap together, substantially as and for the purposes set forth.

2. In a mounting for eyeglasses or spectacles, the combination, with a lens, the spring, and a post formed with a cap or plate, having a groove or channel in its under surface, of a strap loosely and pivotally connected with the lens, and a box portion on said strap arranged in the groove or channel in said cap or plate to prevent lateral motion, oppositely-extending and yielding strap-pieces connected with said post, having their ends in engagement with the edge of the lens, to bind with the same and substantially prevent the pivotal movement of the lens when the parts are secured together, a cushioning means connected with said strap to permit of a movement of said strap in a direction toward the post, and means for positively connecting said spring, post and strap together, substantially as and for the purposes set forth.

3. In a mounting for eyeglasses or spectacles, the combination, with a lens, the spring, and a post formed with a cap or plate, having a groove or channel in its under surface, of a strap, comprising a pair of perforated arms embracing the faces of the lens and a pin or screw in said arms for pivotally securing said strap to the lens, a box portion on said strap, arranged in the groove or channel in said cap or plate of the post, to prevent lateral motion, oppositely-extending and yielding strap-pieces connected with said post, having their ends in engagement with the edge of the lens, to bind with the same and substantially prevent the pivotal movement of the lens when the parts are secured together, a cushioning means connected with said strap to permit of a movement of said strap in a direction toward the post, and means for positively connecting said spring, post and strap together, substantially as and for the purposes set forth.

4. In a mounting for eyeglasses or spectacles, the combination, with a lens, the spring, and a post formed with a cap or plate, having a groove or channel in its under surface, of a strap, comprising a pair of perforated arms embracing the faces of the lens and a pin or screw in said arms for pivotally securing said strap to the lens, a box portion on said strap and a pair of oppositely-arranged and outwardly-projecting lugs on said box portion extending into the groove or channel in said cap or plate of the post, to prevent lateral motion, oppositely-extending and yielding strap-pieces connected with said post, having their ends in engagement with the edge of the lens, to bind with the same and substantially prevent the pivotal movement of the lens when the parts are secured together, a cushioning means connected with said strap to permit of a movement of said strap in a direction toward the post, and means for positively connecting said spring, post and strap together, substantially as and for the purposes set forth.

5. In a mounting for eyeglasses or spectacles, the combination, with a lens and spring, of a post, consisting, essentially, of a cap or plate, and a pair of oppositely-projecting and downwardly-extending yielding strap-pieces connected with said cap or plate, an outwardly-extending part connected with each downwardly-projecting part, extending in opposite directions and having their free ends in holding engagement with the edge of the lens, a strap, a pivotal connection between said strap and lens, and cushioning-lugs connected with said strap to permit of a movement of said strap in a direction toward the post, and means for positively connecting said spring, post and strap together, to substantially prevent the pivotal movement of the lens when the parts are thus secured together, substantially as and for the purposes set forth.

6. In a mounting for eyeglasses or spectacles, the combination, with a lens and the spring, of a post, the cap or plate of said post, a pair of oppositely-projecting yielding strap-pieces, consisting, essentially, of downwardly-extending wire portions e^2 and outwardly-extending parts e^3 , in slidable engagement with the edge of the lens, and arranged to substantially prevent the pivotal movement of the lens when the parts are secured together, a strap, a pivotal connection between said strap and the lens, cushioning-lugs connected with said strap to permit of a movement of said strap in a direction toward the post, and means for positively connecting said spring, post and strap together, substantially as and for the purposes set forth.

7. In a mounting for eyeglasses or spectacles, the combination, with a lens and the spring, of a post, the cap or plate of said post having a pair of longitudinal grooves or channels in its upper surface, yielding strap-pieces having their free ends arranged and held in said grooves or channels and their opposite

- 14
- ends in engagement with the edge of the lens, and arranged to substantially prevent the pivotal movement of the lens when the parts are secured together, a strap, a pivotal connection between said strap and the lens, cushioning-lugs connected with said strap to permit of a movement of said strap in a direction toward the post, and means for positively connecting said spring, post and strap together, substantially as and for the purposes set forth.
8. In a mounting for eyeglasses or spectacles, the combination, with a lens and the spring, of a post, the cap or plate of said post, having a pair of longitudinal grooves or channels in its upper surface, yielding strap-pieces having their free ends arranged and held in said grooves or channels, consisting, essentially, of downwardly-extending wire portions e^2 and outwardly-extending parts e^3 in engagement with the edge of the lens, and arranged to substantially prevent the pivotal movement of the lens when the parts are secured together, a strap, a pivotal connection between said strap and the lens, cushioning-lugs connected with said strap to permit of a movement of said strap in a direction toward the post, and means for positively connecting said spring, post and strap together, substantially as and for the purposes set forth.
9. As a new article of manufacture, a mounting for eyeglasses or spectacles, comprising a lens, a spring, and a post, consisting, essentially, of a cap or plate, having a pair of longitudinal ribs or projections between which the end of the spring is arranged, and having a pair of longitudinal grooves or channels in its upper surface, yielding strap-pieces having their free ends arranged and held in said grooves or channels and their opposite ends in engagement with the edge of the lens, and arranged to substantially prevent the pivotal movement of the lens when the parts are secured together, a strap, a pivotal connection between said strap and the lens, cushioning-lugs connected with said strap to permit of a movement of said strap in a direction toward the post, and means for positively connecting said spring, post and strap together, substantially as and for the purposes set forth.
10. As a new article of manufacture, a mounting for eyeglasses or spectacles, comprising, a lens, a spring, a post, consisting, essentially, of a cap or plate, having a pair of longitudinal ribs or projections between which the end of the spring is arranged, and having a pair of longitudinal grooves or channels in its upper surface, and a longitudinal groove or channel in its under surface, yielding strap-pieces having their free ends arranged and held in said grooves or channels in the upper surface of said cap or plate, a strap, comprising a pair of perforated arms for pivotally securing said strap to the lens, a box portion on said strap arranged in the groove or channel in the under surface of said cap or plate of the post, to prevent lateral motion, and means for positively connecting said spring, post and strap together, substantially as and for the purposes set forth.
11. As a new article of manufacture, a mounting for eyeglasses or spectacles, comprising, a lens, a spring, a post, consisting, essentially, of a cap or plate, having a pair of longitudinal ribs or projections between which the end of the spring is arranged, and having a pair of longitudinal grooves or channels in its upper surface, and a longitudinal groove or channel in its under surface, yielding strap-pieces having their free ends arranged and held in said grooves or channels in the upper surface of said cap or plate, a strap, comprising a pair of perforated arms for pivotally securing said strap to the lens, a box portion on said strap and a pair of oppositely-arranged and outwardly-projecting lugs on said box portion extending into the groove or channel in the under surface of the cap or plate of said post, to prevent lateral motion, and means for positively connecting said spring, post and strap together, substantially as and for the purposes set forth.

In testimony that I claim the invention set forth above I have hereunto set my hand this 14th day of October, 1899.

ADAM LICHT.
